UNITED STATES PATENT OFFICE.

RALPH R. ROOT, OF CLEVELAND, OHIO, ASSIGNOR TO THE GLOBE MACHINE AND STAMPING COMPANY, OF CLEVELAND, OHIO, A CORPORATION OF OHIO.

BOTTLE-CAPPING MACHINE.

1,359,534.

Specification of Letters Patent. Patented Nov. 23, 1920.

Application filed July 17, 1919. Serial No. 311,538.

To all whom it may concern:

Be it known that I, RALPH R. Root, a citizen of the United States, residing at Cleveland, in the county of Cuyahoga and State of Ohio, have invented a certain new and useful Improvement in Bottle-Capping Machines, of which the following is a full, clear, and exact description.

The present invention relates to a device for capping bottles, that is to say, applying what is commonly known as a crown cap to a bottle.

The object of the invention is to provide a device suitable for the use for which it is intended, which is of simple construction and may be made at a low manufacturing cost.

The invention may be generally described as comprising the elements and the combinations thereof set forth in the accompanying claims.

Reference should be had to the accompanying drawings forming a part of this specification, in which Figure 1 is a front elevation of the device with a bottle in position thereon; Fig. 2 is a side elevation; Fig. 3 is a sectional elevation of a portion of the device; Fig. 4 is a sectional elevation showing a modified construction; and Fig. 5 is a fragmentary vertical section of the structure shown in Fig. 4.

Referring to the drawings, the base of the machine is made up of a strip of sheet metal of appropriate length, and width, which is folded into a shape providing extending base members 1 with a substantially cylindrical body portion 2. Means may if desired be provided whereby the base may be attached to a support. The base member which has just been described may be conveniently formed by dies, as a stamping. Extending through the cylindrical portion 2 is a cylindrical piece of wood which is indicated at 3. Pivoted upon the base is a bottle holder or support which comprises a block 4 which block is attached to an upstanding part 5 which is formed to have a back portion and side member 5^a, the front being open.

This member 5 may be formed of sheet metal, and the block 4 secured to the lower portion thereof.

The block 4 has a cylindrical opening such as indicated at 4^a in Fig. 3, which fits upon the cylindrical metal member 2. The

side members 5^a are pivotally secured to the member 3. This may be accomplished in any desired manner, as by means of screws which extend through suitable openings in the side members 5^a, and are secured in the wooden member 3. This construction provides a pivotal mounting for the block 4, and the upstanding member 5 which is attached thereto.

A head 6 is provided with a central die member 7 which has an opening 7^a adapted to engage with a crown closure such as indicated in Fig. 1. This opening 7^a crimps in the side of the crown closure member so that it engages with the annular bead carried by the neck of the bottle which is being capped. The die member 7 is supported by the head 6 and the head at its opposite ends is positioned by means of nuts 10 upon a U-shaped member 11. This U-shaped member comprises upstanding sides 11^a, and a joining portion 11^b. The joining portion 11^b extends through a suitable opening provided in the wooden member 3, and this portion 11^b also engages with struck up straps 13 which are formed in the cylindrical portion 2 of the base.

This U-shaped member is preferably formed as one piece. In assembling the device a straight rod may be inserted through the opening in the member 3 and bent upon opposite sides thereof so as to provide the side member 11^a.

These side members 11^a have a sliding connection with the sides 5^a of the member 5. These connections may be obtained by providing the side member 5^a with a strap portion 14 which may be formed by slipping and pressing a portion of the member 5^a outwardly. It will be noted that the U-shaped member 11 has a pivotal mounting with respect to the member 3 of the base, but this mounting is not concentric with the mounting of the block 4, but is below and to one side of the same. When the base 4 and the upstanding member 5 are moved into the position shown in dotted lines in Fig. 2, the distance between the die 7 and the base block 4 is shortened so that the die member 7 descends toward the head of the bottle, thereby engaging the crown cap and crimping the side edges thereof against the bead carried by the neck of the bottle which is being capped.

Another embodiment of the invention

which embodies the same principle of construction as that heretofore described is also shown in the drawing.

This construction embodies a base block 5 14 which is provided with a longitudinally extending recessed portion generally cylindrical in shape which accommodates a pipe 15.

Secured at the opposite sides of the block 10 14 are side members 16. These side members are secured to the block in any desired fashion, screws 17 being shown for the purpose.

Each side member 16 adjacent the lower 15 portion thereof is provided with a semi-circular recess 16^b and the edge of this recess is turned inwardly as indicated at 16^c, the said flange or inturned portion engaging with the inside wall of the pipe 15. 20 This forms a connection between the side member and the pipe which connection permits the rocking of the block 14 and the side member 16 with respect to the pipe 15.

In the foregoing construction no rear 25 closure member is provided as it is figured that the bottle being capped will usually be held in place by the operator.

In order to accommodate different lengths 30 of bottles I have provided a construction whereby an auxiliary block 18 may be employed, the same being positioned upon the block 14 thereby shortening the distance between the block and the die which crimps the stopper about the end of the bottle.

35 For the purpose of holding the auxiliary block in place, I provide the block 18 with grooves 18^a at its opposite ends and I also provide the end member 16 with short in-turned ribs 19. These ribs may be formed 40 by pressing inwardly a portion of the metal which forms the side members 16. These ribs or ridges 19 are adapted to engage with the grooves in the block when the same is positioned thereby preventing displacement 45 of the auxiliary block 18.

The pipe 15 co-operates with a base member 20. This base member is formed with a central upstanding portion 20^a which is of proper conformation to receive the pipe 50 15. The pipe 15 is secured to the portion 20^a in any desired manner. The member 20 may be formed as a stamping.

A yoke member, the same as that previously described, may be employed, which 55 yoke member has a transversely extending portion 21 which extends beneath the portion 20^a of the base 20.

As before described, this yoke member is conveniently formed from a single piece 60 of the bar stock so that the bottom and the side members are integral.

The portion 21 of the yoke is held in position with respect to the base 20 by having tangs 20^b struck up from the base member 65 20 which engage beneath the portion 21

of the block, thereby holding the same against displacement.

It will be noted that the relative position of the portion 21 of the yoke with respect to the center of rotation of the block 14 is 70 precisely the same as that which has heretofore been described so that the same action in operation is inherent to this construction as in that which has been previously described. 75

The side members of the yoke extend upwardly along the side member 16 heretofore described and have a sliding action therewith similar to that shown in Figs. 1 80 and 2.

Having described my invention what I claim is:—

1. A bottle capping machine comprising a pivoted member, a head and support for the head, said support being pivoted eccentrically with respect to the said pivoted member, and said pivoted member and support having a sliding connection. 85

2. A bottle capping machine comprising a pivoted member, a head, a support for the head, said support being pivoted eccentrically with respect to the said pivoted member and below the pivotal point of said pivoted member, the said pivoted member and support having a sliding connection. 90

3. A bottle capping machine comprising a base, a pivoted member mounted upon said base, a head located above the base, a support for said head, said support being pivoted upon the said base eccentrically with respect to the pivoted member, and said support having its pivotal point located beyond the pivot for the pivoted member, the said pivoted member and support having a sliding connection. 95 100

4. A bottle capping machine comprising a base member, a pivoted member mounted upon the base member, said pivoted member being provided with sides, a head, a support for the head, said support having a sliding connection with the aforesaid sides, said support being pivotally mounted in the base at a point eccentric and below the pivotal point of the pivoted member. 110

5. A bottle capping machine comprising a base, a pivoted member mounted upon the base, a head, a U-shaped support for said head, said support having a portion which extends through the base and pivoted therein, the said support of the U-shaped member 115 in the base being eccentric with respect to the said pivoted member. 120

6. A bottle capping machine comprising a base having a rounded portion, a pivoted member mounted upon the base and having a portion which co-operates with the rounded portion of the base, a head, a supporting member for the head, said supporting member being pivoted upon the base eccentrically with respect to the said pivoted member, 125 130

the pivoted member and support having a sliding connection.

7. A bottle capping machine comprising a base member having a cylindrical portion, a pivoted member mounted to move concentrically with the said rounded portion of the base said pivoted member being provided with upstanding sides, a head, a support for the head, said support having side members which have a sliding connection with the upstanding sides of the pivoted member, said support being pivotally mounted upon the base at a point eccentric with respect to the cylindrical portion thereof.
- 10 8. A bottle capping machine, comprising a stationary cylindrical member, a support which engages with the cylindrical member, side members carried by the support, a yoke pivotally secured with respect to the cylindrical member, said yoke having a sliding connection with the side members, the said side members having inturned flange portions by which the side members have a rocking engagement with the cylindrical member, and a top member carried by the said yoke.
- 15 9. A bottle capping machine comprising a cylindrical member, a support having a portion which fits upon said cylindrical member, said support having side members, said side members being formed at a portion thereof with inturned flanges which engage with the inner side of the cylindrical member, thereby permitting a rocking sliding movement upon the cylindrical member, a yoke having a portion which extends be-

neath the cylindrical member and having side portions, the side members being provided with a flange having an opening through which the side members of the yoke 40 extend and a head carried by the side members of the yoke.

10. A bottle capping machine, comprising a base member, a cylindrical member carried by the base member, a support mounted upon the cylindrical member, side members for the support, each of said side members being provided with an inturned flange which engages with the inner wall of the cylindrical member, a yoke having a portion 50 which is pivotally secured upon the base member, said yoke having side members which have a sliding engagement with the first mentioned side members and a top member carried by the side members of the 55 yoke.

11. A bottle capping machine, comprising a cylindrical member, a support pivotally mounted upon the said cylindrical member, said members secured to the support, each 60 of said side members being formed with an inwardly extending rib, a block having grooves in the ends and adapted to slidely engage the said ribs, a yoke having a portion which is pivoted beneath the cylindrical member, said yoke having side members which have a sliding engagement with the first mentioned side members, and a head carried by the side members of the yoke.

In testimony whereof I hereunto affix my 70 signature.

RALPH R. ROOT.
